UNITED STATES PATENT OFFICE.

AMOS F. DIXON, OF NEWARK, NEW JERSEY, ASSIGNEE, BY MESNE ASSIGNMENTS, TO
WESTERN ELECTRIC COMPANY, INCORPORATED, A CORPORATION OF NEW YORK.

SWITCH-SELECTOR.

1,173,254.

Specification of Letters Patent. Patented Feb. 29, 1916.

Application filed December 12, 1914. Serial No. 376,844.

To all whom it may concern:

Be it known that I, AMOS F. DIXON, a citizen of the United States, residing at Newark, in the county of Essex and State 5 of New Jersey, have invented certain new and useful Improvements in Switch-Selectors, of which the following is a full, clear, concise, and exact description.

This invention relates to switch selectors, 10 and more particularly to a selecting mechanism suitable, for example, for use in the keyboard transmitter of a printing telegraph system. Its object is to provide a device of positive action containing a minimum of pivoted construction and one in which the particular combination of 15 switches, selectively set up by any key is automatically maintained until the purpose of its selection has been accomplished and 20 one which at the same time guards against such a switch combination being overlapped by a succeeding switch selection.

To these ends my invention provides a series of movable switch members which are 25 normally held in contact with a corresponding set of stationary contact points but which may be moved into contact with another set of contact points. These switch members are carried on a set of armatures 30 associated with an electromagnetic device whose function it is to lock the said members in either their normal or their selected 35 contacting positions. The movement of the various switch members is controlled by a series of mechanical actuating devices which 40 may be selectively operated by the key levers of a transmitter key board of the type mentioned above.

This invention will be more clearly understood by referring to the accompanying drawings in which—

Figure 1 gives a plan view of the working parts of a keyboard transmitter employing the selective mechanism of my invention: Fig. 2 gives a sectional view along line 2—2 of Fig. 1 and Fig. 3 gives a view along line 3—3 of Fig. 2 showing further details of the selecting mechanism.

In the adaptation of this invention herein 50 illustrated, a keyboard similar to that of a typewriter is employed. According to the well known arrangement of such keyboards, each key button 5 is attached to one end of a key lever 6 which may be pivoted at its 55 other end to the frame work 7 in any suit-

able manner. Each key lever 6 carries one or more downwardly extending lugs 8 adapted upon the depression of its key 5 to engage and depress one or more of the five bars 9, and the bar 10, which are located beneath key levers 6 and extend at right angles thereto. Located in each end of the bars 9 and also of bar 10 is a diagonal slot 11 whose walls form a track adapted to move on a roller 12 and to give to the bars 60 9 and 10 a longitudinal displacement when they are depressed by the lugs 8. Springs 13 are provided for restoring these bars to their normal positions when the key pressure is released.

Bar 10 has at its right extremity, an upwardly extending arm 14 which actuates the circuit control switch springs 15 upon each longitudinal thrust of the bar 10. Situated to the left of the keyboard is a bi-polar electromagnet 20. Located above the pole pieces of magnet 20 are a series of armatures 21 centrally pivoted at 22 and attractive to one or the other of the pole pieces of magnet 20 depending upon the comparative 70 lengths of the two air gaps between the said pole pieces and the armature. Each armature 21 carries a contact arm 23 which is insulated therefrom by block 24. Arms 23 are normally held in contact with stationary 75 contact points 25 by the spring 26, and electrical connection may be established with arms 23 by way of spring 26 and binding post 27. The armatures 21 in the embodiment of the invention herein illustrated are 80 five in number, corresponding to the five bars 9 of the keyboard. Each bar 9 carries a terminal actuating member 28 which, when the bar 9 is depressed, forces the corresponding armature 21 against the tension 85 of spring 26 into a position where it more nearly closes the air gap 29, at the same time removing arm 23 from its contact with point 25 and bringing it into contact with an opposite contact point 30. When, 90 however, the magnet 20 is energized, the pull on the armature 21 is such that in case this armature is in its normal position, the arm 23 cannot be moved away from contact point 25 by the pressure of a key lever 6, 95 and if the armature 21 is in its operated position the tension of spring 26 is not sufficient to move arm 23 away from contact point 30.

In Fig. 3, for the sake of simplicity, only 100 105 110

2

one of the springs 26 and binding posts 27 are shown, though it should be understood that there is one of each of these parts associated with each of the arms 23.

5 In the operation of the key board transmitter herein described, the depression of a key 5 causes the downward movement and longitudinal displacement of certain of the bars 9 depending upon the combination of 10 lugs 8 carried by the lever arm 6 of the particular key 5 depressed. These bars 9 by means of their actuating members 28 depress the corresponding armatures 21 and move the contact members 23 into engagement with contact points 30. The members 15 23, corresponding to the bars 9, which have not been depressed, will remain in contact with contact points 25. Contact points 25 may, as in this instance, be connected to the 20 negative pole of a source of current and the contact points 30 may be connected to the positive pole of the said source. There is thus set up in the selecting mechanism a combination for controlling a definite train 25 of negative and positive impulses corresponding to the letter or symbol of the key 5 which has been depressed. Furthermore, each key 5 causes a depression and a longitudinal displacement of the bar 10 which 30 closes the normally open contact between springs 15. The closure of this contact energizes the magnet 20 and holds the contact arms 23 in the several positions given them by the operation of said key. After the 35 train of impulses, above noted, has been transmitted, the circuit of magnet 20 may be opened and contact arms 23 returned to their normal positions by their respective springs 26 and a new combination of the arms 23 40 may be set up by the depression of another of the keys 5.

What is claimed is:

1. A switch selector comprising a plurality of movable switch members, an armature individual to each of said members, an actuating arm coöperating with each of said armatures to move the member individual thereto, manual means for selectively operating said actuating arm, an electromagnet for locking said members in their selected positions, and a circuit-closing device actuated by said manual means for energizing said electromagnet.

ture individual to each of said members, an actuating arm coöperating with each of said armatures to move the member individual thereto, manual means for selectively operating said actuating arm, an electromagnet for locking said members in their selected 45 positions, and a circuit-closing device actuated by said manual means for energizing said electromagnet.

2. A switch selector comprising a plurality of movable switch members, means for holding said members in a normal position, an armature individual to each of said members, an actuating arm coöperating with each of said armatures to move the said member individual thereto, a plurality of 50 key levers for selectively operating said actuating arms, an electromagnet for holding said switch members in their selected positions and locking the unselected members in their normal positions, and a circuit-closing 55 device actuated by said key levers for energizing said electromagnet.

3. A switch selector comprising a plurality of movable switch members, an armature individual to each of said members, an actuating arm coöperating with each of said armatures to move the members individual thereto, means for selectively operating said actuating arms, an electromagnet for locking said selected members in their selected 70 positions and locking the unselected members against selection, and a circuit-closing device actuated simultaneously with said switch selection for energizing said electromagnet.

In witness whereof, I hereunto subscribe my name this 11th day of December, A. D., 1914.

AMOS F. DIXON.
